US0D1103594S

(12) **United States Design Patent** (10) **Patent No.:** **US D1,103,594 S**
(45) **Date of Patent:** **** Dec. 2, 2025**

(54) **SHOE**

(71) Applicant: **Birkenstock IP GmbH**, Linz am Rhein (DE)

(72) Inventor: **Barbara Storch**, Linz am Rhein (DE)

(73) Assignee: **Birkenstock IP GmbH**, Linz am Rhein (DE)

(**) Term: **15 Years**

(21) Appl. No.: **29/855,717**

(22) Filed: **Oct. 6, 2022**

Related U.S. Application Data

(62) Division of application No. 35/513,005, filed on Oct. 13, 2021 (U.S. filing date under 35 U.S.C. 384), and having an international filing date of Oct. 13, 2021, now Pat. No. Des. 978,490.

(57) **CLAIM**

The ornamental design for a shoe as shown and described.

DESCRIPTION

FIG. 1 is a front perspective view of the shoe showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines and the grayed-out surface inside of broken lines depict portions of the shoe sole that form no part of the claimed design.

1 Claim, 7 Drawing Sheets
